(72) Inventor: **Jeffery O. Wood**, Belmont, MS (US)

* cited by examiner

(73) Assignee: **Wood Industries Inc.**, Belmont, MS (US)

Primary Examiner — Ralf Seifert

(**) Term: **15 Years**

(74) Attorney, Agent, or Firm — Waller Lansden Dortch & Davis, LLP; Matthew C. Cox

(21) Appl. No.: **29/582,902**(57) **CLAIM**(22) Filed: **Oct. 31, 2016**

What is claimed is the ornamental design for a “compressor,” as shown and described.

(51) LOC (10) Cl. ..... **15-02****DESCRIPTION**(52) U.S. Cl. **USPC D15/9**

FIG. 1 is a front perspective view of the “compressor” of Applicant’s invention.

(58) **Field of Classification Search**

FIG. 2 is a back perspective view of the “compressor” of Applicant’s invention.

USPC D15/7-9; D23/231, 232, 225; 417/60,
417/235, 265, 321, 355, 358, 363, 359,
417/410.1, 415-416, 405, 900, 269, 539,
417/234; 60/408, 412; 184/26-37;
415/140-147; 123/495, 509; 137/565.34

FIG. 3 is a right side elevation view of the “compressor” of Applicant’s invention.

CPC F02M 37/04; F02M 37/14; F04B 53/92;
F04B 1/005

FIG. 4 is a left side elevation view of the “compressor” of Applicant’s invention.

See application file for complete search history.

FIG. 5 is a front elevation view of the “compressor” of Applicant’s invention.

(56) **References Cited**

FIG. 6 is a back elevation view of the “compressor” of Applicant’s invention.
